UNITED STATES PATENT OFFICE

1,967,234

DROP-SEAT GARMENT

Erick O. Fellroth, Minneapolis, Minn., assignor
to Martin Brothers Company, Minneapolis,
Minn., a corporation of Minnesota

Application January 25, 1933, Serial No. 653,357

6 Claims. (Cl. 2—78)

My invention relates to combination garments and particularly to garments constructed with a body portion having pants and a waist and formed with an opening at the rear, and further having a drop seat covering said opening.

An object of the invention resides in providing a garment in which the drop seat is easily manipulated and readily moved from closing to lowered position and vice versa.

10 A still further object of the invention resides in providing a garment in which the drop seat may be effectively applied to the garment to close the opening in the garment and to fit upon the person of the wearer in a manner to give freedom 15 and comfort to the wearer.

An object of the invention resides in providing a garment having belt straps connected to the drop seat and adapted to be secured together at the front to form a belt encircling the body of 20 the wearer.

Another object of the invention resides in providing a garment having auxiliary straps connected to the belt straps and to the drop seat for holding up the ends of the belt when the drop 25 seat is lowered.

An object of the invention resides in providing guides on the body of the garment with respect to which said auxiliary straps may slide in the moving of the drop seat from closing to lowered 30 position and vice versa.

Another object of the invention resides in employing loops for guiding said auxiliary straps and in attaching said loops to the body of the garment.

35 A still further object of the invention resides in constructing the drop seat with a waist band and in forming the belt straps in continuation of said waist band.

An object of the invention resides in arranging 40 said belt straps and auxiliary straps coextensive with one another.

A feature of the invention resides in attaching the auxiliary straps to the drop seat at the waist band and in proximity to the lateral edges of the 45 drop seat.

Other objects of the invention reside in the novel combination and arrangement of parts and in the details of construction hereinafter illustrated and/or described.

50 In the drawing:

Fig. 1 is a perspective view of a garment viewed from the front thereof and illustrating an embodiment of my invention.

Fig. 2 is a perspective view of the garment 55 shown in Fig. 1 and viewed from the rear thereof.

Fig. 3 is a perspective view of a portion of the garment viewed from the rear and illustrating the drop seat lowered.

In garments with drop seats and particularly in garments used for small children where the 60 belt straps are attached to the drop seat considerable inconvenience arises when the drop seat is lowered and hangs in a loose manner therefrom, due to the ends of the belt straps frequently falling into the bowl or being trampled 65 upon. Where the belt straps are guided, the belt straps frequently bunch together or as termed in the trade, become "roped", making it difficult to manipulate the same and causing discomfort to the wearer. The present invention overcomes 70 these difficulties by providing a simple and effective device for holding up the belt straps when the drop seat is lowered and for supporting the drop seat when the drop seat is in closing position.

My improved garment consists of a body portion 75 which I have indicated in its entirety at A. This body portion comprises pants 10 which have attached to them a waist 11. These parts will now be described in detail.

These pants 10 comprise legs 12 and 13 which 80 are constructed with seams along the sides of the garment as indicated at 18. These seams extend partially along the legs of the pants leaving the rear portion of the garment free from the body portion above the ends of said seams. By 85 means of this construction the pants are divided into a front portion 14 and a rear portion 15, the latter portion terminating in a drop seat 16 adapted to be held in position as shown in Fig. 2 or to be lowered as illustrated in Fig. 3. The 90 legs 12 and 13 are further secured together along a forward seam 20 and a rearward seam 21, which seams unite in the crotch of the garment. The pants 10 are open at the front and are constructed with a placket 17 for closing such opening. But- 95 tons not shown are employed for securing the placket to the body of the garment and said placket is constructed to form a fly to cover said buttons.

The waist 11 comprises a front 22 and a back 100 23 which are stitched together along the shoulders of the garment as indicated at seams 24 and along the sides of the garment to form seams 25. The waist preferably is open at the front thereof and is provided with a placket 27 which may be 105 closed through buttons 26. The waist 11 further includes arm holes 28 and 29 and a collar 30 which are constructed and attached to the waist in the usual manner. The front 22 of the waist 11 is connected at its lower end to the upper por- 110

tion of the front 14 of pants 10. If desired, these parts of the garment may be formed of the same sheet of material and continuous. These parts may however be separately formed and connected together through buttons or in any other suitable manner. In either case the placket 27 forms a continuation of the placket 17 so that the entire garment may be opened along the front thereof from the neck to the crotch.

10 At the rear of the garment the back 23 of waist 11 is formed with a lower portion or tail 31 which extends somewhat below the waist line of the garment which is indicated at 32. This tail is secured to the front 14 of the pants 10 by means 15 of seams 33 which lie in continuation of the seams 18 previously referred to. By means of this construction an opening 34 is formed at the rear of the garment between the back 15 of the pants and the back 23 of the waist which opening 20 is indicated at 34. When the drop seat is in closing position the same covers the opening 34 and the lateral edges 35 and 36 of the drop seat extend along the portions of the pants adjacent the seam 33.

25 At the upper end of the drop seat 16 is provided a waistband 37 which is disposed at the waist line 32 of the garment. This waistband extends up to the lateral edges 35 and 36 of said drop seat. In continuation of this waistband are 30 two belt straps 38 and 39 which are provided at the ends thereof with complementary buckle members 40 and 41. The belt straps 38 and 39 may be formed of the same piece of material as the waistband 37 or the said belt straps may be constructed separately and connected to the drop seat or to the waistband 37 in any suitable manner. In either event these belt straps preferably lie in continuation of said waistband. When the drop seat is raised the two belt straps 38 and 39 40 protrude forwardly of the garment, where the same may be secured together through the complementary buckle members 40 and 41 to hold the drop seat in closing position as shown in Fig. 1.

In conjunction with the two belt straps 38 and 45 39 two auxiliary belt straps 42 and 43 are employed which are of substantially the same length as the belt straps 38 and 39. These two auxiliary straps are connected at corresponding ends thereof to the straps 38 and 39 near the free ends of said belt straps. Said auxiliary straps are attached at their other ends to the waistband 37 in proximity to the lateral edges 35 and 36 of the drop seat. The straps 42 and 43 are substantially coextensive with the straps 38 and 39 so that the 50 same lie smoothly upon the body of the wearer when the belt straps are hooked together as shown in Figs. 1 and 2. The straps 42 and 43 are connected to the belt straps 38 and 39 short of the extreme ends of said straps to provide free ends 55 48 and 49 on said belt straps to which the buckle members 40 and 41 may be attached. The two auxiliary belt straps 42 and 43 slide through wire loops 50 and 51 which are mounted in tabs 52 and 53 secured to the tail 31 of the body A at the elevation of the waist line 32 of the garment. By 60 means of this construction the auxiliary straps are connected to the body through the loops 50 and 51 and serve to support the drop seat and prevent the same from sagging.

65 70 In the closing position of the drop seat the auxiliary straps 42 and 43 underlie the belt straps 38 and 39 and the tabs 52 and 53 together with loops 50 and 51 underlie the waistband 37, all of said parts being completely concealed thereby.

75 When the drop seat is lowered the two auxiliary

straps 42 and 43 hold up the ends of the belt straps 38 and 39. The two auxiliary straps 42 and 43 are preferably considerably narrower than the belt straps 38 and 39 and the two loops 50 and 51 are considerably larger than said straps 80 and are formed curved. By means of this construction roping is entirely prevented and the auxiliary straps are caused to slide freely through the loops.

In the form of the invention shown in Figs. 2 and 3 the lateral edges 35 and 36 of the drop seat are caused to taper so that the length of the waist band 37 is considerably less than the distance measured along the waist line of the wearer from one seam 33 to the other. For this reason the loops 50 and 51 are attached to the tail or lower portion 31 of the waist intermediate the two seams 33. With the parts so constructed the loops 50 and 51 serve to hold the tail 31 within the drop seat thereby making it impossible to pull the tail out of the pants when the garment is worn by a child. If desired, however, the drop seat can be made of full width across the top bringing the lateral edges 35 and 36 thereof up to the seams 33 when the drop seat is in closing position. When so arranged the loops 50 and 51 would be attached to the garment in proximity to the seams 33. With such construction the opening 34 is entirely clear.

The use of the garment is exceedingly simple. 105 When the drop seat is to be lowered, buckle members 40 and 41 are disengaged and the drop seat grasped by the waist band 37 and drawn downwardly. This causes the auxiliary straps 42 and 43 to slide in the loops 50 and 51 bringing the 110 drop seat into the position shown in Fig. 3. In such position the auxiliary straps 42 and 43 are free from the garment so that the opening 34 may be opened the full width by the moving of the straps laterally. In raising the drop seat into 115 closing position the two belt buckle members 40 and 41 are grasped and moved toward the front of the garment. This causes the auxiliary straps 42 and 43 to slide through the loops 50 and 51 which draws the drop seat upwardly and into closing position. As the belt straps 38 and 39 approach the forward position of the body of the wearer, the drop seat is automatically brought into closing position and the tail 31 drawn into the pants proper through the downward pull exerted upon the loops 50 and 51. When the drop seat is in closing position the ends of the auxiliary straps 42 and 43 are in close proximity to the loops 50 and 51 and assist in supporting the drop seat. In such position the lateral edges 35 and 120 36 of the drop seat overlie the portions of the tail between the loops 50 and 51 and the seams 33.

125 Where the loops 50 and 51 are attached to the garment in proximity to the seams 33 the garment may be constructed in two pieces in which case the 130 said loops are attached to the pants at the waist line thereof. Where the two garments are permanently connected together the said straps may be connected to the waist intermediate the two 135 seams 33 thereby assisting in holding the waist tail within the pants.

140 My invention is highly advantageous in that an extremely simple and practical device is provided whereby drop seats may be easily and conveniently manipulated. By means of the auxiliary straps the ends of the belt straps are held up when the drop seat is lowered. By forming the auxiliary straps narrower the usual difficulty occasioned through roping is entirely prevented. The auxiliary straps and loops are complete- 145 150

ly concealed when the drop seat is in closed position. By use of the auxiliary belt straps, large and inexpensive loops constructed of wire may be employed instead of the usual more expensive construction. A garment constructed in accordance with my invention is extremely neat and attractive in appearance and the various parts remain in proper position throughout the use of the garment and at the same time give the user 10 freedom and comfort. Where the loops are attached to the garment intermediate the side seams thereof, said loops serve to assist in holding the tail of the garment within the pants.

Changes in the specific form of my invention, as herein disclosed, may be made within 15 the scope of what is claimed without departing from the spirit of my invention.

Having described my invention, what I claim as new and desire to protect by Letters Patent 20 is:

1. A garment including a waist and pants, the latter having a drop seat, the upper marginal portion thereof, in the closed position of said seat, being substantially coincident with the 25 waist line of the garment, said waist having a tail normally covered by said upper marginal portion of said seat, belt straps attached to said seat at its said upper marginal portion, said belt straps having means at their free ends for releasably connecting the same together at the 30 front of the garment, auxiliary straps, one for each belt strap, each auxiliary strap being connected at one end thereof to the inner side of its respective belt strap at its free end and connected at the other end thereof to the inner side 35 of said upper marginal portion of the drop seat adjacent to the junction between its respective belt strap and said seat, guides secured to the tail of the waist in position to be covered by 40 said upper marginal portion of said seat, one guide being provided for each auxiliary strap and each guide being located substantially in coincidence with the point occupied by the junction 45 between its respective auxiliary strap and said seat in the closed position of the latter, each of said straps being threaded in its respective guide and slidably cooperating therewith to pull the drop seat upwardly and bring it smoothly into place when the belt straps are brought together about the body of the wearer, and further 50 cooperating with its respective guide to hold up the drop seat and hold down the tail of the waist.

2. A garment including a waist and pants, the latter having a drop seat, the upper marginal 55 portion thereof, in the closed position of said seat, being substantially coincident with the waist line of the garment, said waist having a tail normally covered by said upper marginal portion of said seat, belt straps attached to said seat at its said upper marginal portion, said belt straps having 60 means at their free ends for releasably connecting the same together at the front of the garment, auxiliary straps, one for each belt strap, each auxiliary strap being connected at one end thereof to its respective belt strap and connected at the other end thereof to said upper marginal portion of the drop seat, guides secured to 65 the tail of the waist in position to be covered by said upper marginal portion of said seat, one 70 guide being provided for each auxiliary strap, each of said straps being threaded in its respective guide and slidably cooperating therewith to pull the drop seat upwardly into place when the

belt straps are brought together about the body of the wearer, and further cooperating with its respective guide to hold up the drop seat and hold down the tail of the waist.

3. A garment including a waist and pants, the latter having a drop seat, belt straps attached to said seat and having means at their free ends for releasably connecting the same together at the front of the garment, auxiliary straps, one for each belt strap, each auxiliary strap being connected at one end thereof to its respective belt strap at its free end and connected at the other end thereof to the drop seat, guides secured to the back of the waist, one guide being provided for each auxiliary strap, each guide being located substantially directly above the junction between its respective auxiliary strap and said seat, each of said auxiliary straps being threaded in its respective guide and slidably cooperating therewith to pull the drop seat upwardly when the belt straps are brought together about the body of the wearer, and further cooperating with its respective guide to keep the raised seat and the back of the waist in place.

4. A garment including a waist and pants, the latter having a drop seat, belt straps attached to said seat and having means at their free ends for releasably connecting the same together at the front of the garment, auxiliary straps, one for each belt strap, each auxiliary strap being connected at one end thereof to its respective belt strap at its free end and connected at the other end thereof to the drop seat, guides secured to the back of the waist, one guide being provided for each auxiliary strap, each of said auxiliary straps being threaded in its respective guide and slidably cooperating therewith to pull the drop seat upwardly when the belt straps are brought together about the body of the wearer, and further cooperating with its respective guide to keep the raised seat and the back of the waist in place.

5. A garment including a waist and pants, the latter having a drop seat, belt straps having means for releasably connecting the free ends thereof together at the front of the garment, auxiliary straps, one for each belt strap, each auxiliary strap being connected at one end thereof to its respective belt strap at its free end and connected at the other end thereof to the drop seat, guide means for said auxiliary straps secured to the back of the garment, said auxiliary straps cooperating with said guide means to bring the drop seat into place when the belt straps are brought together about the body of the wearer.

6. In a garment, pants having a drop seat, belt straps attached to said seat and having means at their free ends for releasably connecting the same together at the front of the garment, auxiliary straps, one for each belt strap, each auxiliary strap being connected at one end thereof to its respective belt strap at its free end and connected at the other end thereof to the drop seat, guides secured to the back of the garment, one guide being provided for each auxiliary strap, each of said straps being threaded in its respective guide and slidably cooperating therewith to pull the drop seat upwardly into place and thus hold it when the belt straps are brought together about the body of the wearer.

ERICK O. FELLROTH.
